(57) **CLAIM**

The ornamental design for a hook for a shower curtain, window treatment, or the like, as shown and described.

DESCRIPTION

FIG. 1 is a perspective view of a hook for a shower curtain, window treatment, or the like showing my new design;

FIG. 2 is a right side elevation view thereof, the left side elevation view being a mirror image;

FIG. 3 is a rear elevation view thereof;

FIG. 4 is a front elevation view thereof;

FIG. 5 is a top plan view thereof; and,

FIG. 6 is a bottom plan view thereof.

1 Claim, 4 Drawing Sheets
